United States Patent Office

Des. 219,724

Patented Jan. 12, 1971

219,724

FOLDABLE COMB

Arthur Rogovin, 245 Rumsey Road,
Yonkers, N.Y. 10701

Filed June 17, 1970, Ser. No. 23,532

Term of patent 14 years

Int. Cl. D28—03

U.S. Cl. D86—8

FIG. 4

FIG. 1

FIG. 2

FIG. 3

FIG. 1 is a side elevational view of a foldable comb showing my new design;

FIG. 2 is an enlarged edge elevational view thereof;

FIG. 3 is a side elevational view of the side opposite that shown in FIG. 1 with the handle in a partially foldable position, each part of the handle being foldable over the adjacent side edge; and

FIG. 4 is an enlarged top plan view of FIG. 1.

I claim:

The ornamental design for a foldable comb, substantially as shown and described.
